UNITED STATES PATENT OFFICE.

JOHN FILKIN, OF MONTCLAIR, NEW JERSEY.

CARPENTER'S GAGE.

No. 920,941.

Specification of Letters Patent.

Patented May 11, 1909.

Application filed October 21, 1908. Serial No. 458,770.

To all whom it may concern:

Be it known that I, JOHN FILKIN, a citizen of the United States, and a resident of Montclair, in the county of Essex and State of New Jersey, have invented certain new and useful Improvements in Carpenters' Gages, of which the following is a specification.

My invention relates to gages for use of carpenters and wood workers.

10 Among the objects of the invention are to provide a simple, reliable form of gage which can be cheaply constructed, and which will be extremely accurate and which may be used for a variety of operations.

15 With these and related purposes in view, my invention consists of the parts, improvements and combinations hereinafter set forth and claimed.

Reference is hereby made to the accompanying drawings, which illustrate preferred embodiments of my invention, but it is to be understood that these drawings are illustrative merely, and that changes and modifications may be resorted to therein, so long as 25 the same come within the scope of my claims.

In the said drawings, wherein the same reference numerals are used to designate the same parts throughout, Figure 1 is an isometrical view of the simplest form of gage; Fig. 2 is a similar view of my improved gage, made in two separable and relatively adjustable portions, Fig. 3 is a similar view, but looking at the back of the gage shown in Fig. 2, the parts of the gage being reversed from 30 the position shown on Fig. 2 and showing a straight edge secured to the gage. Fig. 4 is a rear elevation of a slightly modified form of gage. Fig. 5 is a side view partly in section showing one form of my improved gage in 35 use in securing in place upon the rafters of a roof the roof strips, or strips to which the shingles or slates will be directly secured. Fig. 6 is a similar view of the same gage in use for spacing shingles, and Fig. 7 is a view similar to 5 and 6 of one form of my improved gage as used for spacing clapboards or weather-boarding.

The device shown in Fig. 1 is intended for use in shingling and in fastening roof strips. 50 This simplest form of gage is preferably made from a metal sheet, and if preferred may be made by a single stamping operation. The body of this gage is designated by the reference numeral 1, and at its base, the oppositely extending flanges 2 and 3 are formed. Near the upper end and preferably at one

side, the flange 4 is formed, extending in the same direction as the flange 3. The body 1 is extended at 5 to form an upwardly extending portion provided with perforations 60 6, 6, which permit the fastening of a straight edge 7 to the gage by means of nails, screws or other fastening devices, the flange 4 serving as a stop to assure the proper position of the straight edge. The body 1 is provided 65 with spikes 8 which are situated preferably near the flanges 2 and 3, and extend in the same direction as these flanges. In the construction shown, these spikes are formed by stamping at the same time the flanges are 70 formed, but it is evident that spikes formed on or secured in any way to the gage will answer the same purpose. In use, two or more of the gages are secured to the straight edge at intervals along its length, two such 75 gages being commonly made use of, one near each end of the straight edge. When the device is used for fastening roof strips as shown in Fig. 5 the gage is temporarily secured to the roof strip last fastened, (shown 80 at 9 in Fig. 5, the rafters being shown at 10) by means of the spike 8, the flange 3 which is brought up against the lower edge of the last strip fastened, serving to correctly position the gage in place. In this position, the 85 gage lies flat on the upper faces of the roof strips as shown in the drawing just referred to. The roof strip next to be fastened is laid on the rafters and brought down against the straight edge and secured in place. The 90 straight edge and attached gages are then lifted and the spike 8 withdrawn, and the succeeding strips are secured in the same way. All the gages attached to the straight edge being identical, it is possible in this way 95 to secure all the roof strips to the rafters without any preliminary marking or measuring, and any slight errors which may be made in the placing of the roof strips in exact parallelism may be compensated for by measuring the 100 distances for the last three or four strips, and then dividing among these few strips whatever discrepancies may be found to exist. When the roof strips have been fastened, the 105 device is used in precisely the same way, except that it is reversed, for fastening the shingles, which must be spaced same distance apart as the roof strips, in order that the nails for fastening the shingles may be driven through the same part of each row of shingles. The use of the device for this purpose is shown in Fig. 6. Here the flange 2

serves to position the gages against the bottom of the row of shingles last fastened in place, and the gage lies flat upon the shingles, the row of shingles next to be fastened being brought down against the face of the straight edge in the same manner as has already been explained with reference to the roof strips.

The device shown in Figs. 2 and 3 is the same as that shown in Fig. 1 except that it is made up of two parts 21 and 22 adjustable relative to one another, and but a single flange 23 is provided at the bottom of the portion 21 for the reason that the upper portion and lower portions may be reversed with relation to one another as shown in Figs. 2 and 3. The main body portion 21 of this device is provided with a spike 24 secured thereto in any convenient way, and a threaded stem 25 is provided upon this portion of the gage on which a wing nut 26 may be screwed. The remaining element 22 of the gage is provided with a slot 27 which receives the stem 25 and is also provided with an upwardly extending portion 28 through perforations in which the gage may be secured to the straight edge. This portion of the gage is likewise provided with a flange 29 terminating in a spike 30. The spike 30 is narrower than the flange 29, thus providing shoulders at its junction therewith which serve to limit the distance to which the spike may be inserted in a board or other object. In Fig. 3 this device is shown attached to a straight edge in the position in which it is used for fastening shingles in place in the same general manner as has already been described with reference to the gage shown in Fig. 1. When this device is used for fastening roof strips, the wing nut 26 is loosened and the two portions of the gage detached from one another and reversed so that the flange 23 is turned in the same way as the flange 29. The gage is shown assembled in this relation in Fig. 2 and its use will be readily understood from the already described use of a similar gage as shown in Fig. 6. This form of gage may also be used for fastening weather boarding or clapboards, upon the side of a house, as shown in Fig. 7. When used for this purpose, no straight edge is needed. The spikes 24 and 30 are pushed into the last clapboard fastened in place, the flange 23 being brought firmly against the bottom of said clapboard, and the next clapboard to be fastened is laid upon the flange 29. Two or more gages are used at different points along the length of the clapboard to be fastened, as will be understood. As shown in Fig. 3, the spike 30 of the flange 29 does not interfere with the use of the device in fastening shingles or roof strips, as the straight edge used for these purposes is thicker than the clapboard, the straight edge being usually one inch thick and the clapboard five-eighths of an inch in

thickness at its bottom, and the spike does not project below the lower surface of the straight edge.

The accurate relative adjustment of the two parts of the gage last described may be provided for in any approved fashion. As shown in Fig. 2, scales are marked on the body portion 21, the scale at the right in this figure indicating the distance between the upper face of the flanges 23 and 29, and determining the distance apart at which clapboards are to be placed. The scale at the left indicates the distance between the flange 23 and the top surface of the straight edge which is usually two inches wide, so that in the drawing this scale is marked to show distances two inches greater respectively than the corresponding distances of the clapboard scale at the right. This difference, of course, depends upon the width of the straight edge in common use.

In Fig. 4, a slight modification is illustrated, the body portion 22 being provided with upstanding and down turned lugs 31 and 32 which fit into a series of openings 33. In the position shown the lug 32 is fitted into one of the perforations, but when the parts of the gage are reversed with relation to one another, the lug 31 will be fitted in any desired opening as will be readily understood. These holes are spaced a predetermined distance apart, and serve to regulate the spacing of clapboards, roof strips or shingles. This arrangement assists in securing the two parts of the gage together, but for all ordinary purposes it will be found that these parts are secured together with sufficient security by means of the wing nut 26.

Having now described my invention and the operation thereof, I claim:

1. A carpenter's gage provided with means whereby a straight edge may be secured to it on either face at one end thereof, and having means at the opposite end for determining the position of the straight edge with respect to the work when the gage is placed on top of the straight edge or beneath the same, substantially as set forth.

2. A carpenter's gage comprising two members removably and adjustably secured together, one of the members being provided with means whereby it may be secured to a straight edge and also provided with means for positioning the straight edge, and the second member being provided with means for positioning the gage with respect to the work, and with means for removably securing the gage in place, substantially as set forth.

3. In a carpenter's gage the combination of a member provided with means by which it may be secured to a straight edge and having a flange to determine the position of the straight edge with relation thereto, and a second member removably and reversibly connected to the first named member and pro-

- vided with means for positioning the gage with respect to the work, whereby the device may be used with the gage placed beneath or on top of the straight edge, substantially as 5 set forth.
4. In a carpenter's gage, the combination of a member having an upstanding portion provided with perforations to permit its being secured to a straight edge and having a 10 flange or lug to determine the position of the straight edge with respect thereto, and provided with a central slot and a co-acting member provided with an end flange and a screw threaded shank taking into the slot in 15 the first named member and a thumb screw on the said shank whereby the two members of the gage may be removably, adjustably and reversibly connected together, substantially as set forth.
- 20 5. In a carpenter's gage, a member provided with an upstanding portion having a lug or flange extending at right angles thereto and terminating in a spike, a second member adjustably secured to the first named mem-
- ber and provided with means for positioning 25 the gage with respect to the work, substantially as set forth.
6. In a carpenter's gage, the combination of a member provided with an upstanding portion and a lug or flange extending at right angles thereto, said lug or flange having straight, substantially parallel sides for a distance substantially equal to the thickness of an ordinary clapboard or weather-board, and terminating in a spike, shoulders being 30 formed at the junction of the spike with the lug, and a second member adjustably and removably connected to the first named member, and provided with means for positioning the gage with respect to the work and with 35 means for removably securing it in place, substantially as set forth.

This specification signed and witnessed this
19 day of October 1908.

JOHN FILKIN.
